CLAIM

The ornamental design for a bunt training baseball bat,
as shown and described.

DESCRIPTION

FIG. 1 is a perspective view of a bunt training baseball
bat showing my new design;

FIG. 2 is a side elevational view thereof, the undis-
closed opposite side being identical;

FIG. 3 is a top plan view thereof, the undisclosed oppo-
site side being identical;

FIG. 4 is a front end elevational view thereof; and,

FIG. 5 is a rear end elevational view thereof.
